UNITED STATES PATENT OFFICE

KARL FASSNACHT, OF PROVIDENCE, RHODE ISLAND, ASSIGNOR TO SPEIDEL CHAIN CO., OF PROVIDENCE, RHODE ISLAND, A FIRM COMPOSED OF FEEDERIC SPEIDEL AND EUGEN SPEIDEL, BOTH OF PFORZHEIM, GERMANY

ORNAMENTAL CHAIN

Application filed May 25, 1928. Serial No. 280,581.

This invention relates to an ornamental chain, and has for its object to provide a link which may have an ornament or gem mounted therein without the use of solder. 5 A still further object of the invention is the provision of a link formed from sheet metal with an opening therein and bendable arms extending into said opening, which arms, by their bending, may receive and 10 mount an ornamental gem in bead-like form in the link.

With these and other objects in view, the invention consists of certain novel features of construction, as will be more fully described, and particularly pointed out in the appended claims.

In the accompanying drawings:

Figure 1 is a top plan view of a chain showing the gems as mounted in position. 20 Figure 2 is a side elevation thereof.

Figure 3 is a perspective view of one of the links previous to its having a gem mounted therein.

Figure 4 is a sectional side view with the 25 arms of the link bent in position for receiving the gem.

Figure 5 is a side elevation showing the gem in one of the positions it assumes in being mounted in the link.

Figure 6 is a sectional side view showing the gem as mounted in the link.

Figure 7 is a perspective view of two of the links in their finished form connected together.

Figure 8 is a perspective view of a modified showing with the arms soldered to the edges of the opening.

It is found in the construction of chains for personal adornment of the character in 40 which ornaments such as gems or the like are to be positioned in the links, that, if any soldering operations are used for their mounting, the lustre of the gem is diminished to an appreciable extent, and in order 45 to avoid this undesirable result, I have formed the mounting in such a way that no soldering operation is necessary while the gem is positioned in the link, by cutting the link from sheet stock with an opening therein and providing arms extending toward

each other which may be bent upward to extend into a gem having a recess or hole therein to receive the ends of said arms and thus hold the same in position in said opening; and the following is a detailed description of the present embodiment of this invention and showing the preferred means by which these advantageous results may be accomplished. 55

With reference to the drawings, 10 designates the body part of the link which is cut from sheet stock with an opening 11 therein having integral arms 12 and 13 extending toward each other from opposite sides of the opening, which arms are bendable upward as illustrated at 14 in Figure 4 to receive an ornament or gem 15 shown in bead-like form with a hole 16 therethrough and the end portions 17 and 18 of the arms are bent as illustrated in Figure 5 to enter the hole 16 in the ornament which may then be moved into position in the openings as illustrated in Figure 6, which bends the arms back into position in the general plane of the body part of the links as shown in Figures 6 and 7, and retains the ornaments centrally with the link openings, due to the engagement of the sides of the arms with the hole 16. 70 75

In Figure 8, the arms 22 and 23 are soldered as at 24 to the edges of the opening 11 instead of being integral therewith, as illustrated in Figure 3. However, the method of mounting is the same and such construction would be used only where the body part of the link is desired to be formed of material of such stiffness that it would not permit bending of the arms which are cut from the stock thereof. 80 85

Any suitable means may be used for connecting the links together and I have here shown the same as being connected by slots 19 and 20 in opposite ends of the body link and using a loop connector 21 to connect these links together in series, as desired. 95 Also the links may be slightly curved to conform to the part which they may encircle.

The foregoing description is directed solely towards the construction illustrated, 100

but I desire it to be understood that I reserve the privilege of resorting to all the mechanical changes to which the device is susceptible, the invention being defined and limited only by the terms of the appended claims.

I claim:—

1. In a chain for personal adornment, an ornamental link having a body part with an opening therethrough, arms attached to said body part positioned in the plane of the link and extending laterally into said opening, and an ornament having means to receive said arms to hold it in said opening spaced from the sides thereof.
2. In a chain for personal adornment, an ornamental link having a body part with an opening therethrough, an ornament having a hole therethrough, and means in said hole positioned in the plane of the link and attached to opposite sides of the opening in the body part to support said ornament in said opening spaced from the sides thereof.
3. In a chain for personal adornment, an ornamental link having a body part with an opening therethrough, an ornament having a hole therethrough, and an arm in said hole positioned in the plane of the link and attached to the body part to support said ornament in said opening spaced from the sides thereof.
4. In an ornamental chain comprising a series of links flexibly connected together, an opening in each link positioned inwardly from the periphery thereof, bendable arms in each link positioned in the plane of the link extending toward each other into said opening, and an ornament having recess means to receive said arms and hold the ornament suspended in said opening spaced from the sides thereof.
5. In a chain for personal adornment, an ornamental substantially flat link having a body part with an opening therein positioned inwardly from the periphery thereof, a pair of arms integral with said body part and extending toward each other into said opening from opposite sides thereof, and an ornamental bead in said opening with the said arms positioned in the hole thereof to support it in position spaced from the sides thereof.
6. In a chain for personal adornment, an ornamental substantially flat link formed of sheet metal with a portion cut out inwardly from its edge to form an opening therethrough and leave integral bendable arms in the plane of the link and extending toward each other into said opening, an ornamental bead having a hole therethrough mounted in said opening by said arms extending into said hole from the opposite ends thereof.

In testimony whereof I affix my signature.
